UNITED STATES PATENT OFFICE.

PERCY SHEPHERD MERRILL, OF WATERVILLE, MAINE.

WRENCH.

1,092,071.

Specification of Letters Patent. Patented Mar. 31, 1914.

Application filed September 5, 1913. Serial No. 788,242.

To all whom it may concern:

Be it known that I, PERCY S. MERRILL, a citizen of the United States, and a resident of Waterville, in the county of Kennebec and the State of Maine, have invented a new and Improved Wrench, of which the following is a full, clear, and exact description.

The object of the invention is to provide an inexpensive, simple and strong wrench having the features of a nut and pipe wrench, the handle of which can be adjusted to permit the use of the wrench in places where a special wrench, that is, either a straight or a bent wrench, is required. I obtain the above object by providing a shank having an extension in the shape of a sector, a jaw pivotally mounted on the shank and associated with the sector, a second jaw slidably and adjustably mounted on the shank and coöperating with the first jaw, and a handle adjustably mounted on the sector whereby the wrench is manipulated.

The invention consists of the construction and combination of parts to be more fully described hereinafter and fully set forth in the claims.

Reference is to be had to the accompanying drawings forming a part of this specification, in which like characters indicate corresponding parts in all the views and in which:

Figure 1 is a side elevation of an embodiment of my invention, the dotted line showing a different position of the adjustable jaw and also of the handle; and Fig. 2 is an end view in the direction of the arrow 2 as shown in Fig. 1.

Referring to the drawings, 3 represents a shank, one end of which is extended and bent into a sector 4 lying in the same plane with the shank, with the end of the sector lying in proximity of the end of the shank.

Pivotaly mounted on the end of the shank by means of a, preferably riveted, pin 5 is a jaw 6, which jaw straddles over the end of the shank by the engagement of the said end with a central recess 7 formed in the jaw and fitting snugly on said end. One end 7' of this recess is beveled and therein receives a spring 8 secured in the beveled end in any suitable way with one end and having the opposite end bearing against the smooth edge of the shank. The opposite edge of the shank is threaded in the customary way

and adapted to be engaged by the worm member 9 rotatably mounted in the movable jaw 10 which is slidably mounted on the shank 3. This jaw 10 coöperates with the jaw 6. The end of the jaw 6 disposed toward the sector 4 is bifurcated, forming a recess 11 which is engaged by the rounded end of the sector 4. This end of the jaw is also provided with a pin 12 and is engaged by a slot 13 formed in the end of the sector 4. Engaging the sector 4 by means of a groove 14 is a handle 15 of any suitable shape, the curvature of the groove 14 being similar to the curvature of the sector, so that the handle can be moved on the sector as shown in dotted line, Fig. 1. A set screw 16 is provided in the head of the handle engaging the sector so that the handle 15 can be clamped in any desired position on the sector.

The facing surfaces of the jaws 6 and 10 are preferably indented or milled so as to better grip the object between the jaws. The provision of the beveled end 7' in the recess 7 of the jaw 6 permits the face of the jaw 6 to move toward the face of the jaw 10 when the handle 15 is pulled in the direction of the arrow shown in Fig. 1, causing the sector 4 to deflect from the shank 3 about the reduced portion of the material 17 which connects the shank to the sector. This deflection of the sector is most prominent at the free end of the same, where the slot 13 is formed and which slot is so positioned with respect to the pivot 5 that when it moves away from the pivot it causes the pin 12 to slide on the sides of the groove as an inclined plane, thereby causing the end of the jaw 6 provided with a milled face to move toward the milled face of the jaw 10. The movement of the end of jaw 6 toward the end of jaw 10 permits the use of the wrench for nuts or pipes, or, for example, for nuts having round edges.

When the wrench is used the handle 15 is always pulled in the direction of the arrow as shown in Fig. 1, thereby there is always a tendency for the end of the jaws 6 to move toward the end of the jaw 10, thus gripping the object engaged therebetween, this tendency being due to the flexibility of the material in the bend 17 obtained by reducing the said portion which forms the connection between the shank and the sector. The handle 15 on the sector 4, by means of the set screw 16, can be adjusted and secured in any

desired portion of the sector, thereby permitting the use of the wrench in some places where it would require only a straight wrench and other places where it would require only a bent wrench, or several wrenches.

It is understood that while the sector shown in the drawings is preferably of rectangular section, if it is desired the same 10 can be made of circular cross section or any other shape.

It can be seen from the drawings that when the wrench is used for regular hexagonal or square nuts, the edges of which 15 are not round, the handle 15 can be pulled in a direction opposite to the one indicated by the arrow in Fig. 1 without in any way affecting the relation between the shank and the sector, in view of the fact that the pin 20 12 abuts against the end of the groove 13.

Having thus described my invention, I claim as new and desire to secure by Letters Patent:

1. In a wrench,—a shank having a resilient extension forming a sector and adapted to be deflected from said shank; a jaw pivotally mounted on said shank and movably associated with said sector; a jaw slidably and adjustably mounted on said shank and 25 coöperating with said pivotally mounted jaw; and a handle mounted on said sector and having means whereby it can be secured in any position on said sector, and whereby said sector can be deflected from said shank, substantially as and for the purpose set forth.

2. In a wrench,—a shank having a resilient extension forming a sector and adapted to be deflected from said shank; a jaw pivotally mounted on said shank and loosely connected to said sector; a jaw slidably and adjustably mounted on said shank and coöperating with said pivotally mounted jaw; and a handle slidably and adjustably 40 mounted on said sector whereby said sector can be deflected angularly from the shank, substantially as and for the purpose set forth.

3. In a wrench,—a shank having a resilient extension forming a sector and adapted to be deflected from said shank; a jaw pivotally mounted on the end of the shank and loosely connected to the end of the sector; a jaw slidably and adjustably mounted on 50 said shank and coöperating with said pivotally mounted jaw; and a handle slidably and adjustably mounted on said sector whereby said sector can be deflected angularly from the shank, substantially as and for the purpose set forth.

4. In a wrench,—a shank having a resilient extension forming a sector the end of which is adjacent the end of the shank adapted to be deflected therefrom; a jaw

pivotaly mounted on the end of said shank and loosely connected with one end to the end of the sector, whereby the said second end of said jaw can move toward said shank; a second jaw slidably and adjustably mounted on said shank and coöperating with the pivotally mounted jaw; and a handle adjustably mounted on said sector whereby the end of the sector can be deflected from the end of the shank, substantially as and for the purpose set forth.

5. In a wrench,—a shank having an extension forming a sector lying in the same plane with the shank and the end of which is adjacent to the end of the shank; a jaw having a recess engaging the end of said shank; a pivot connecting said jaw with said end of shank, said jaw having a bifurcated end engaging the end of said sector; a pin in said bifurcated end, the end of said sector engaging the bifurcated end having a slot engaged by said pin, said slot being so formed with reference to said pivot that when the end of said sector is caused to move away from the end of the shank said jaw is caused to move on the pivot with its non-bifurcated end moving toward the shank; a jaw slidably and adjustably mounted on said shank coöperating with said pivotally mounted jaw; a handle slidably mounted on said sector; and means in said handle whereby it 95 can be secured at any desired point on said sector.

6. In a wrench,—a shank having an extension, forming a sector lying in the same plane with the shank, the end of the said sector being adjacent to the end of the shank; a jaw having a central recess, one end of which is beveled, said jaw straddling the end of the shank with said recess engaging said end; a pivot connecting the jaw to the 100 said end; a spring in said beveled end of the recess engaging the shank and normally forcing the end adjacent the spring away from the shank, said jaw having a bifurcation at the opposite end engaging the end of 105 the sector, said end of sector having a slot; a pin positioned in the bifurcated end of the jaw and engaging said slot; a jaw slidably mounted on said shank and coöperating with the pivotally mounted jaw; 110 means in said jaw and on said shank whereby said second jaw can be adjusted in any desired position on said shank; a handle engaging said sector; and means on said handle whereby the same can be secured in any 115 desired position on said sector, said slot in said sector being so formed with respect to said pivot that when said end is moved away by said handle from the end of said shank, said pivoted jaw will move on its pivot with 120 the non-bifurcated end moving toward the adjustably mounted jaw.

7. In a wrench,—a shank; a sector in the

same plane with the shank; means resiliently connecting one end of said shank and sector, the opposite ends of said shank and sector being in proximity with each other; a handle adjustably mounted on said sector whereby the free end of said sector can be moved away from the end of said shank, the resilient connection between the shank and sector normally tending to restore said sector to its original position; a jaw pivotally mounted on the end of the shank and loosely connected with one end to the end of the

sector; a jaw slidably mounted on said shank; and means in said pivotally mounted jaw normally tending to force the non-connected end of said jaw away from the adjustable jaw. 15

In testimony whereof I have signed my name to this specification in the presence of two subscribing witnesses.

PERCY SHEPHERD MERRILL.
